UNITED STATES PATENT OFFICE.

ELIGAH H. FIELD, OF BUFORD, GEORGIA, ASSIGNOR OF ONE-HALF TO JAMES T. SCALES,
OF BUFORD, GEORGIA.

FIRE ALARM.

Application filed April 1, 1921. Serial No. 457,614.

To all whom it may concern:

Be it known that I, ELIGAH H. FIELD, a citizen of the United States, residing at Buford, in the county of Gwinnett and State 5 of Georgia, have invented a new and useful Fire Alarm, of which the following is a specification.

This invention relates to alarm systems and more particularly to automatically controlled fire alarms, it being the primary object of the invention to provide a novel means for causing an alarm to be sounded in the various rooms throughout a building, if a fire occurs in any room of the building 10 15 in which an alarm is positioned.

A further object of the invention is to provide a novel means for connecting a plurality of alarms, whereby the operation of one alarm will operate to actuate the associated alarms.

With the foregoing and other objects in view which will appear as the description proceeds, the invention resides in the combination and arrangement of parts and in 20 25 the details of construction hereinafter described and claimed, it being understood that changes in the precise embodiment of the invention herein disclosed, may be made within the scope of what is claimed, without departing from the spirit of the invention.

Referring to the drawings:—

Figure 1 is a vertical sectional view through rooms of a building disclosing the alarms as applied to the ceilings thereof.

Figure 2 illustrates a detail view of an alarm disclosing the actuating means.

Referring to the drawings in detail, the device includes a plurality of alarms indicated at 5, which alarms are of well known 40 constructions, and embody a pivoted controlling lever 6 which operates to release a spring controlled tapper employed for sounding the alarm.

The controlling lever 6 of the alarm of 45 compartment A, is held in its neutral position as by means of the coiled springs 7 and 8, which coiled springs have connection with the controlling lever 6 as by means of the fusible connections 9.

Having connection with one end of the coiled spring 8, is a fusible link 10, which 50 normally holds the spring 8 in an expanded position to place the same under tension, the link 10 being shown as anchored to one wall 55 of a room as by means of the fusible cord 11.

The spring 7 which also has connection with the controlling lever 6, has connection with a fusible link 12, which link connects with the fusible link 13 of the adjacent room, as by means of the fusible cord 14, 60 which is shown as passing through the guard 22 and over suitable pulleys indicated at 15, disposed in the rooms or compartments adjacent to the ceilings thereof.

The fusible link 13 has connection with 65 the coiled spring 16 which in turn connects with the controlling lever 6 of the alarm associated therewith, which coiled spring 16 being under tension will operate to move the controlling lever 6 in one direction should 70 the equalizing spring, which also has connection with the controlling lever 6 at the opposite side thereof become released from its anchorage.

Associated with the spring 16 is the 75 equalizing spring 17 that also has connection with the controlling lever associated with the coiled spring 16, and this coiled spring 17 has connection with the alarm positioned in the adjacent upper room, through the 80 fusible cord 18 and fusible link 19.

It might be further stated however that the controlling lever 6 of each alarm is provided with a bifurcated extremity 20 and that the fusible cords 9, which have connection therewith through the medium of the links 21, are positioned over the furcations. Due to the connection between the cords 9 and controlling lever 6, it is obvious that when the lever 6 swings laterally in either 90 direction, the links 21 will become disconnected from the controlling lever.

In the operation of the device, assuming that a fire is started in compartment A, and the fusible link 10 or cord 11 is burned. 95 The coiled spring 7 being under tension, moves the controlling lever 6 of the alarm associated therewith laterally, setting off the alarm. The tension of the coiled spring 7 also causes the link 21 to slide off of the 100 controlling lever which permits the tension of the spring 16 to draw the fusible cord 14, which results in the coiled spring 17 moving the controlling lever of the alarm associated therewith, setting off this alarm.

While I have shown and described adjacent rooms as provided with the alarms, it is to be understood that any number of rooms of a building may be supplied with these alarms, the construction of the alarms 110

being such as to cause an alarm to be sounded in each of the various rooms, when a fire takes place in any of the other rooms of the building.

5 Having thus described the invention, what is claimed as new is:—

In combination with an alarm including a pivoted controlling lever having a bifurcated extremity, fusible cords having links secured thereto, said links being positioned over opposed furcations of the lever, coiled spring members having connection with the respective fusible cords, and disposed on op-

posite sides of the alarm the spring members being of equal tensions to normally hold the 15 controlling lever in its inactive position, and means having connection with the spring members for normally holding the spring members under tension.

In testimony that I claim the foregoing 20 as my own, I have hereto affixed my signature in the presence of two witnesses.

ELIGAH H. FIELD.
